A. GRILLI,
SCREW PROPELLER,
FILED MAY 16, 1921.

Paul M. Hunt.

WITNESS:

UNITED STATES PATENT OFFICE.

ANGELO GRILLI, OF MILWAUKEE, WISCONSIN.

SCREW PROPELLER.

Application filed May 16, 1921. Serial No. 470,111.

To all whom it may concern:

Be it known that I, ANGELO GRILLI, a subject of the King of Italy, residing at Milwaukee, in the county of Milwaukee and 5 State of Wisconsin, have invented new and useful Improvements in Screw Propellers, of which the following is a specification.

This invention relates to improvements in ship propellers and has for an object the 10 provision of a propeller which includes means for increasing its efficiency by increasing its thrust upon the water and at the same time eliminating jar and vibration.

15 With the above and other objects in view, the invention further includes the following novel features and details of construction, to be hereinafter more fully described, illustrated in the accompanying drawings and 20 pointed out in the appended claim.

In the drawings:—

Figure 1 is a side view of a propeller constructed in accordance with the invention.

Figure 2 is an end view of the same.

25 Figure 3 is a side view taken at an angle of 90° with respect to Figure 1.

Referring in detail to the drawings, wherein like characters of reference denote corresponding parts, the reference character 30 10 indicates the hub of the propeller which is surrounded by a spiral worm 11, the latter having a plurality of convolutions. The spiral worm merges into the hub 10 and the space between the flanges of the spiral 35 provides a spiral passage having inlet and outlet ends disposed upon opposite sides of and located at each end of the hub.

Each of these spiral passages is provided

at its end with blades 12, which form a continuation of the spiral worm 11 and which 40 have their cutting edges 13 disposed radially from the hub 10, the said cutting edges being reversely arranged at each end of the propeller.

When the propeller is in motion, these 45 cutting edges enter the water with a minimum amount of resistance and as the spiral worm forms a continuation of the blades 12, the propeller will pass through the water with the least possible amount of forward 50 resistance, while its rear end will leave the water with a minimum amount of drag.

The propeller is so constructed as to travel through the water with equal facility in either direction and is preferably provided 55 at each end of the hub with an inset portion 14 which surrounds the bore 15 of the hub, the inset portion 14 accommodating suitable fastening devices for securing the propeller upon a shaft. 60

The invention is susceptible of various changes in its form, proportions and minor details of construction and the right is herein reserved to make such changes as properly fall within the scope of the appended 65 claim.

Having described the invention what is claimed is:—

A propeller provided at each end of the hub with an inset portion surrounding the 70 bore of the hub and adapted to accommodate suitable fastening devices for securing the propeller upon a shaft.

In testimony whereof I affix my signature.

ANGELO GRILLI.
